UNITED STATES PATENT OFFICE.

WILLIAM EARNEST HARRIS, OF LONG BEACH, CALIFORNIA.

LOCKING DEVICE.

Application filed March 7, 1923. Serial No. 623,416.

To all whom it may concern:

Be it known that I, WILLIAM E. HARRIS, a citizen of the United States, residing at Long Beach, in the county of Los Angeles 5 and State of California, have invented a new and useful Locking Device, of which the following is a specification.

This invention relates to motor vehicle bodies, and more particularly motor vehicle 10 bodies of the closed type.

The primary object of the invention is to provide novel means for holding the sliding window sections thereof against movement when in their closed positions, the device 15 being especially adapted for use in connection with sliding window sections.

Another object of the invention is to provide a structure of this character which may be readily and easily applied to structures now in use, eliminating the use of 20 making alterations in the structure for applying the same.

With the foregoing and other objects in view which will appear as the description 25 proceeds, the invention resides in the combination and arrangement of parts and in the details of construction hereinafter described and claimed, it being understood that changes in the precise embodiment of 30 The invention herein disclosed, may be made within the scope of what is claimed, without departing from the spirit of the invention.

Referring to the drawings:

35 Figure 1 is a side elevational view of a closed body of the type employing a securing device constructed in accordance with the invention.

Figure 2 is a transverse sectional view 40 through the upper spaced rails of the top, and disclosing the device in its inactive position.

Figure 3 is a detail view of one of the bracket members.

45 Figure 4 is a plan view disclosing the securing members as mounted between the upper side rails of the top, and

Figure 5 is a side elevational view thereof.

50 Referring to the drawings in detail, a motor vehicle body is shown as equipped with a winter top to close the upper portion thereof, the top being indicated at 5 and supplied with sliding window sections

55 6. Each window section is provided with a pair of bracket members 7 which are

disposed in spaced relation with each other along the upper edges of the window sections, the upper ends of the bracket members extending inwardly and downwardly 60 providing spaces for the rollers 8 that support the window sections.

Mounted between the rails 11 of the top 5, is a track bar 9 that includes track sections 10 and 12, the section 12 being designed to accommodate one window section while the track section 10 accommodates the adjacent window section and permits the sections to move one behind the other when the windows are moved to their 70 open positions.

The bar 9 is pivotally supported at its upper end by means of the bolt 13, the opposite end thereof being supplied with a bolt 14 operating in the elongated opening 75 15 of the side rails 11 so when the track bar 9 is bent downwardly, as indicated in dotted lines in Figure 5 of the drawings, the movement of the bar 9 may be compensated for at this point. 80

Supported by the side rails 11, is a shaft 16 which is supported in the bearings 17 secured to the upper surfaces of the side rails, the shaft 16 being supplied with a cam 18 adapted to move into engagement 85 with the upper surface of the track bar 9 to move the same downwardly so that the flanges 19 formed at the upper edge of the bar 9 may contact with the upper edges of the bracket members 7 and force the same 90 into engagement with the lower rails of the top 5 in a manner to prevent rattling thereof.

An operating handle 20 is provided at one end of the shaft 16 so that the shaft may 95 be readily operated to accomplish this result.

At the lower end of each window frame, is a cushioning member indicated 21, which 100 is in the form of a length of rubber positioned in a suitable recess formed in the bottom of each window frame, the cushioning member being designed to permit such binding action to take place and at the same time relieve the window frame of undue 105 strain.

In the use of the device, assuming that the window sections have been moved to their closed positions and it is desired to lock them against movement, the handle 20 110 is operated to move the cam 18 into engagement with the track bar 9, whereupon the

track bar moves downwardly into engagement with the upper edges of the brackets, forcing the window sections downwardly as described.

5. What I claim as new is:—

In a closed body construction including spaced upper side rails, a track bar pivotally supported between the rails at one of its ends, said side rails having elongated openings, a bolt carried by the opposite end of the track bar and movable in the elongated openings, window sections operating under the track bar and carrying rollers movable

on the track bar, and means disposed above the track bar and contacting therewith for 15 moving the track bar and window sections to create a binding action between the window sections and their frames.

In testimony that I claim the foregoing as my own, I have hereto affixed my signature in the presence of two witnesses.

WILLIAM EARNEST HARRIS.
